UNITED STATES PATENT OFFICE

2,599,261

BILFOLD WITH UNSTITCHED CENTER PANEL

Edgar Hughes, Joplin, Mo., assignor to The Meeker Company, Inc., Joplin, Mo., a corporation of Missouri

Application June 28, 1951, Serial No. 233,962

3 Claims. (Cl. 150—38)

1

This invention relates to improvements in billfolds or pocket wallets, particularly of the kind shown in the Elliff Patent No. 2,514,042 dated July 4, 1950.

One of the principal objects of the present invention is to provide a billfold with an unstitched center panel which slides longitudinally as the billfold is folded and unfolded. Another object of this invention is to provide a simple and cheap center panel construction for a billfold that eliminates pasting or stitching as well as cloth end portions and several operations in manufacture.

Still another object of this invention is to provide a billfold with a smaller bottom opening at the fold line thereby improving the appearance of the billfold. A still further object is to provide two readily accessible hidden pockets each approximately half the length of the unfolded billfold.

These and other objects and advantages will become apparent hereinafter.

This invention is embodied in a billfold comprising a full length pocket having an outer side wall and panels forming portions of the inner side wall, each of said panels having a longitudinal slit therein, and an unstitched center panel which bridges the space between said panels, said center panel having tongues thereon which cooperate with said slits so that said center panel slides longitudinally with respect to said panels as said billfold is folded and unfolded.

The invention also consists in the parts and in the combinations and arrangements of parts hereinafter described and claimed.

In the accompanying drawings, which form part of this specification, and wherein like numerals and symbols refer to like parts wherever they occur:

Fig. 1 is a plan view of the blank from which a billfold embodying my invention is made,

Fig. 2 is a plan view of the partition member for the full length pocket of the billfold,

Fig. 3 is a plan view of the novel center panel which bridges the space between the two end pockets,

Fig. 4 is an inner side elevational view of the unfolded billfold,

Fig. 5 is a top plan view of the unfolded billfold.

Fig. 6 is a vertical cross-sectional view taken along the line 6—6 of Fig. 5 showing the inner walls of the end pockets and the inside flap of the novel center panel, and

Fig. 7 is a vertical cross-sectional view taken through the full length pocket after said billfold

has been folded and shows the center panel in its innermost position in the end pocket.

In the accompanying drawings, my invention is shown embodied in a billfold of the kind having a pocket A, which extends the full length of the billfold and is open along the top edge thereof, and end pockets B that open toward the transverse medial fold line of the billfold and overlie each other when the billfold is folded on said fold line.

This billfold comprises a blank of leather or other flexible material that is shaped to provide an oblong body panel, which forms the outer wall 1 of the full length pocket A, and end panels that form the outer walls 2 of the end pockets B. The outer wall 1 of the full length pocket A has a narrow upper marginal finishing flap 3 that extends from end to end thereof, a small lower marginal finishing flap 4 that is folded over and adhesively secured to the inner face of said wall at the transverse medial fold line thereof, and two lower marginal locking flaps 5 that extend from the finishing flap 4 to the ends of said wall and are notched, as at 6, at their ends to provide locking tongues 7 at their free corners.

The outer wall 2 of each end pocket B has an upper marginal flap 8 of the same size and shape as said outer wall, and a lower marginal locking flap 9 which is notched, as at 10, to provide locking tongues 11 at its free corners, the locking flap 9 being of the same size and shape as the locking flaps 5 along the lower margins of the outer wall 1 of the long pocket A. The upper marginal flap 8 of the outer wall 2 of each end pocket B has a longitudinal slit 12 along its free margin; and said flap is folded upon the inner face of said wall to form the inner wall of said end pocket. Each inner wall forming flap 8 is also provided with a short longitudinal slit 13 near the outer margin thereof as shown in Fig. 1, said slits 13 being near the fold line when said billfold is folded. The locking flap 9 along the lower margin of the outer wall 2 of the end pocket is folded over and adhesively secured to the other face of the folded-over inner wall forming flap 8 below the slit 12 therein and the free margin of said locking flap inserted in said slit. The folded end pocket forming portions 2, 8 and 9 are folded over the inner face of the outer wall 1, and the adjacent locking flap 5 along the lower margin of said outer wall is folded upon the locking flap 9 and its margin also inserted in the slit 12 and adhesively secured to the similarly inserted margin of the locking flap 9 and to the inner face of the inner wall forming flap 8 of the end pocket, the

55

locking tongues at the ends of the two locking flaps extending beyond the ends of the slit 12 and thus preventing said locking flaps from being pulled out of said slit. A liner 14 of paper or other suitable material of the same size and shape of the inner wall forming flap 8 is then adhesively secured flatwise to the inner face thereof and to the inserted margin of the locking flap 9, thereby entirely covering the joint between said flaps.

This billfold is provided with a center panel 15 of leather or other flexible material. The center panel 15 comprises a facing flap 16 with an inside flap 17 hingedly secured thereto, as at 18. The inside flap 17 has an upper portion 19 and a lower portion 20 and is provided with locking tongues 21 having short longitudinal slits 22 extending inwardly therefrom. The tongues 21 and the slits 22 of the inside flap 17 are adapted to cooperate with the longitudinal slits 13 in the inner walls 8 of the end pockets B.

In assembled position, the ends of the facing flap 16 extend into the opposing mouths of the end pockets B and terminate short of the bottoms thereof. Thus, the facing flap 16 bridges the space between the two end pockets B. The outer edges of the upper portion 19 of the inside flap 17 and the locking tongues 21 are also positioned within the end pockets B. The lower portion 20 of the inside flap 16 is positioned within the full length pocket A. The hinge or fold 18 is at the top of the billfold. When looking into the end pockets B of the assembled billfold only the facing flap 16 is seen. This facing flap 16 covers the upper portion 19 and the locking tongues 21 which also are positioned inside the end pockets B. The facing flap 16 is of sufficient height to extend entirely across the end pockets B and slides freely in and out of the end pockets B as the billfold is folded and unfolded. This construction substantially lessens the size of the bottom opening 23 in the billfold when looking at the inner side of the billfold as in Fig. 4. During the folding and unfolding the tongues 21 and slits 22 slide longitudinally with respect to the slits 13 in the inner walls 8 of the end pockets B. Figs. 6 and 7 show the extreme positions of the center panel 15 in the unfolded and folded positions of the billfold respectively.

Located in the full length pocket A is a longitudinal folded partition panel C of leather or other flexible material which extends substantially from end to end of said pocket and is attached to the upper edge of the outer wall 1 thereof by adhesively securing the upper marginal finishing flap 3 of said outer wall 1 to one longitudinal margin of said panel. The remaining portion of the panel C is left free and extends downwardly, as at 24, in the pocket A alongside the outer wall thereof to form with said wall a hidden or secret compartment, and thence upwardly, as at 25, between said downwardly extending portion and the inner wall of said pocket to form two upwardly opening compartments. Access may be had to the hidden compartment by grasping the free upper margin of the upwardly folded portion 25 of the partition panel and pulling this portion together with the downwardly folded portion 24 of said panel out of the pocket A.

Two smaller secret compartments are also formed with the present center panel 15. These smaller secret compartments are located in the end pockets B and are formed between the inner wall forming flaps 8 and the end facing flap 16. Access may be had to either of these smaller

secret compartments by removing an end of the facing flap 16 from the end pocket B. The smaller secret compartments open toward each other so that the entire space between the facing flap 16 and the inner wall flaps 8 can be used as a full length secret compartment if desired.

The hereinbefore described billfold construction has numerous advantages in addition to those set forth in the Elliff Patent No. 2,514,042 dated July 4, 1950. The bottom opening 23 can be made smaller than with previous forms of center panel constructions. Cloth end portions are eliminated from the center panel and no stitching whatever is required for the center panel. The thickness near the bottoms of the end pockets is reduced since no cloth must be folded upon itself when the billfold is folded. Several steps in manufacture are eliminated.

Obviously, the hereinbefore described construction can be used in other forms of billfolds such as those with bellows folds at the bottoms of the end pockets. It can be used with any construction wherein a space must be bridged in such a manner that the bridge must slide. The hereinbefore described invention admits of considerable modification without departing therefrom except as defined in the claims. Therefore, I do not wish to be limited to the precise arrangements shown and described.

30. What I claim is:

1. A billfold having a full length pocket opening along the upper edge thereof and two end pockets that open toward each other in the unfolded position of said billfold and overlie each other in the folded position of said billfold, said billfold including a panel forming the outer side wall of said full length pocket and having end extensions folded to form the inner and outer side walls of said end pockets and portions of the inner side wall of said full length pocket, each of said inner side walls of said end pockets having a longitudinal slit therein, and a center panel having a facing flap and an inside flap, said facing flap being positioned to bridge the space between said end pockets and slide therein, said inside flap having tongues thereon with longitudinal slits extending therefrom, said tongues on said inside flap being adapted to cooperate with said longitudinal slits in said inner side walls of said end pockets.

2. A billfold having a full length pocket opening along the upper edge thereof and two end pockets that open toward each other in the unfolded position of said billfold and overlie each other in the folded position of said billfold, said billfold including a panel forming the outer side wall of said full length pocket and having end extensions folded to form the inner and outer side walls of said end pockets and portions of the inner side wall of said full length pocket, each of said inner side walls of said end pockets having a longitudinal slit therein, and a center panel having a facing flap and an inside flap with a fold therebetween, said facing flap being positioned to bridge the space between said end pockets and slide therein, said fold positioned at the upper edge of said billfold, said inside flap having tongues thereon with longitudinal slits extending therefrom, said tongues on said inside flap being adapted to cooperate with said longitudinal slits in said inner side walls of said end pockets, said tongues having a longitudinal dimension longer than said longitudinal slit in said inner side walls for preventing said tongues from slipping out of

said slits, said facing flap and said inner side walls forming a hidden compartment.

3. A billfold having a full length pocket opening along the upper edge thereof and two end pockets that open toward each other in the unfolded position of said billfold and overlie each other in the folded position of said billfold, said billfold including a panel forming the outer side wall of said full length pocket and having end extensions folded to form the inner and outer side walls of said end pockets and portions of the inner side wall of said full length pocket, each of said inner side walls of said end pockets having a longitudinal slit therein, said panel having lower marginal flaps that extend upwardly between said panel and said inner side walls of said end pockets and are secured thereto above the lower side edges thereof and form bottom portions of said full length pocket and bellows fold connections between the lower margin of said

10
15
20

panel and the corresponding margins of said inner side walls of said end pockets and a center panel having a facing flap and an inside flap, said facing flap being positioned to bridge the space between said end pockets and slide therein, said inside flap having tongues thereon with longitudinal slits extending therefrom, said tongues on said inside flap being adapted to cooperate with said longitudinal slits in said inner side walls of said end pockets.
